The ornamental design for a horizontal LED lamp, as shown and described.

DESCRIPTION

FIG. 1 is a perspective view from above of a horizontal LED lamp, showing my new design; and

FIG. 2 is right side view thereof;

FIG. 3 is a left side view thereof;

FIG. 4 is a front view thereof;

FIG. 5 is a rear view thereof;

FIG. 6 is a top view thereof; and,

FIG. 7 is a bottom view thereof.

The broken line illustration of environmental and other structures in the drawings are not part of the design sought to be patented.
